LIGHTING FIXTURE PRISM

Carl Wellhofer, Glenside, Pa., assignor to Lighting Corporation of America, Philadelphia, Pa., a corporation of Pennsylvania

Filed Nov. 14, 1966, Ser. No. 4,768

Term of patent 14 years

(Cl. D48—14)

FIG. 1

FIG. 2

FIG. 3

FIG. 4

FIG. 5

FIGURE 1 is a front view of a lighting fixture prism showing my new design;

FIGURE 2 is a side view in elevation thereof;

FIGURE 3 is a rear view in elevation thereof;

FIGURE 4 is a bottom plan view thereof;

FIGURE 5 is a top plan view thereof.

The light fixture prism illustrated in the drawing is substantially transparent.

I claim:

The ornamental design for a lighting fixture prism, substantially as shown and described.
